UNITED STATES PATENT OFFICE.

FRED K. LEWIS, OF ASHTABULA, OHIO.

TOP FOR VEHICLES AND THE LIKE.

Application filed January 11, 1919. Serial No. 270,709.

To all whom it may concern:

Be it known that I, FRED K. LEWIS, a citizen of the United States, and a resident of Ashtabula, county of Ashtabula, and State 5 of Ohio, have invented a new and useful Improvement in Tops for Vehicles and the like, of which the following is a specification, the principle of the invention being herein explained and the best mode in which I have 10 contemplated applying that principle, so as to distinguish it from other inventions.

The object of the present invention is to provide an outrigger structure for automobile tops of the so-called "one man" type, 15 which will be capable of considerably more longitudinal extension than in present designs, while still retaining the essential feature of supporting the top structure wholly from a single main bow. More particularly 20 the object is to provide a structure of the character in question, which may be supported from a single rearwardly inclining main bow, so that when the top is extended the entire tonneau space forwardly of such 25 main bow will be clear of any obstruction, even where such tonneau is a two-seated one. A further object is to provide a structure that may be readily manipulated to either fold or unfold as desired, without it being 30 necessary for the operator to leave the tonneau.

To the accomplishment of the foregoing and related ends, the invention, then, consists of the means hereinafter fully described and particularly pointed out in the 35 claims, the annexed drawing and the following description setting forth in detail certain mechanism embodying the invention, such disclosed means constituting, however, 40 but one of the various mechanical forms in which the principle of the invention may be used.

In said annexed drawing:—

Fig. 1 is a side elevational view of a top 45 supporting structure embodying my present improvements, such top being shown as mounted on an automobile body or tonneau of conventional form; Fig. 2 is a similar side elevational view, but showing the top and such supporting structure in partially collapsed or folded condition; Fig. 3 is a broken plan view of a portion of the structure, as indicated by the line 3—3; Fig. 1;

and Fig. 4 is a transverse section of a detail, the plane of such section being indicated by 55 the line 4—4, Fig. 3.

It is of course a matter of indifference whether the top is used on automobile, motor-boat or otherwise, and, depending upon its longitudinal extent, a smaller or larger 60 number of bows, in addition to the outrigger structure of present interest, may be utilized. It will also be understood that the term "bow" is used herein inclusively to designate not merely the wooden bow proper, but also 65 the metallic sockets carrying the same, these parts when regarded in side elevation constituting the equivalent of the so-called "sticks," as they are called in the old wood structure. It is accordingly a matter of 70 convenience to refer to the parts in the singular, as though the structure lay all in a single vertical plane, since the parts of interest do actually lie in such a plane.

As previously indicated, the top covering 75 1 is designed to be entirely supported through an appropriate outrigger structure from a single main bow 2. The latter, which is of substantial construction in view of the weight it is thus designed to carry, is pivotally supported upon or attached to the body at the point 3 in the usual manner, so that it may be laid down and supported in a substantially horizontal plane when the top is 80 not in use. Normally, in the extended or 85 open condition of the top, said main bow 2 inclines rearwardly at an angle of approximately forty-five degrees to the horizontal, being held from rising higher by the top covering, or rather by special straps (not 90 shown) or extensions of the longitudinal strainers which, as is well known, are used to connect the bows together and provide supporting means for the top covering intermediate between said bows. For the purpose in hand such straps or strainers may 95 be regarded as a part of the covering material.

The outrigger structure comprises a main articulated auxiliary bow, or, as it is sometimes called, outrigger bow 6, the latter term referring more particularly to the outer portion or bow proper, 7, which is secured to the main bow 2 by means of an arm 8 (one on each side of course) pivotally attached to 100 said main bow and to the rear end of such 105

outrigger bow, and so constituting the inner portion of said articulated auxiliary bow 6. The point of attachment of this arm to the main bow is preferably in line with, or just 5 above, the side edge of the cover, so as to be hidden by the latter, and the joint 9 between said arm and the outrigger bow is a rule joint disposed so as to prevent further bending of the arm in question, when extended in 10 horizontal fashion, as in the open condition of the top illustrated in Fig. 1.

Pivots attached to the arm 8 is a supplemental bow 10, that, in such open condition of the top, is designed to extend forwardly at an angle with respect to said arm, 15 so as to support the cover 1 at a point approximately midway between the main bow 2 and outrigger bow 7. Operatively connecting said supplemental bow with the 20 main bow 2 and outrigger bow 7, is a link or brace, preferably comprising three parts pivotally connected together, the intermediate link 11 being pivotally attached to said supplemental bow, and the two 25 other links 12 and 13 being respectively attached to the main bow 2 at a point above the point of pivotal attachment of the arm 8 thereto, and to the outrigger bow 7 at a point beyond the joint 9. All 30 of the joints in this three-part articulated link are freely bending, both those between the links themselves, and those between the two longer links and the main and outrigger bows, respectively, so that the intermediate link 11, which is preferably considerably shorter than the two other links, 35 operates in effect as a double-arm lever or equalizer bar; except the forward link 13 is formed at the end thereof which is pivotally attached to said shorter link 11, with a lateral projection 14 (see Figs. 3 and 4) 40 that is adapted to overlie such shorter link and provide in effect a lock joint at this point in the open or extended condition of 45 the top.

The particular manner in which arm 8 and link 12 are pivotally attached to main bow 2 is a matter of indifference, but preferably a bracket 15 of the form illustrated in 50 Figs. 1 and 2 may be utilized, such bracket being firmly attached to the front face of the main bow, and the upper portion to which the link is attached lying clear of such main bow so as correspondingly to 55 shift forwardly the point of attachment of the link.

The forward longer link 13 extends beyond the point 16 of its pivotal attachment to outrigger bow 7 so as to constitute in 60 effect a lever, the lower end of which projects a trifle below the plane of said bow when the top is open, and attached to such end is a second outrigger bow 17, which supports the extreme forward portion of 65 the top covering 1. In other words, there

are in effect two outrigger bows which support the forward portion of the top covering and permit of a corresponding increase in the longitudinal extent of the latter without requiring a separate forward support resting on the vehicle body. This second outrigger bow 17 is freely pivotally connected with said link, or lever 13, it being observed that the position of the joint is determined by the angular position of the link, which is locked in proper place when the top is open. A separate link 18, however, connects said outrigger bow 17 with the main outrigger bow 7, so that it is supported therefrom without 80 imposing too much strain on the cover material between the two bows.

Said link 18 furthermore serves to correlate the movement of the two outrigger bows when the top is being folded, as will 85 be evident from an inspection of Fig. 2. This same figure clearly illustrates the manner in which the other component parts of the top supporting structure fold up; in other words, the links 13 and 18 maintain 90 the supplemental bow 10 and the two outrigger bows 7 and 17 in substantially parallel arrangement during such folding operation, and equally during the unfolding of the top. In order to fold or collapse the 95 top, it is merely necessary to break the joint 9 by pressing down thereon, whereupon the weight of the parts naturally tends to cause the several bows to fold up in the manner just indicated. As these drop back upon 100 the main bow 2, the latter will fall rearwardly into the approximately horizontal position indicated in dotted outline in Fig. 2, with the bows 10, 7 and 17 folded closely thereagainst, the links that operatively connect said last mentioned bows lying alongside thereof.

The structure is thus seen to be unusually compact in its folded condition, and yet when extended an adequate support for a 110 top of considerable longitudinal extent is provided without any obstruction in the way of a forwardly inclining main bow, or braces or links that lie below the side line of the top covering. The various component bows are joined together by the employment 115 of a minimum number of connecting parts, which need not be of specially heavy construction, in order to afford a rigid and entirely satisfactory support.

It will be understood of course that when the top is extended, the second or extreme forward outrigger bow is attached or tied down to the wind-shield as indicated by the dotted line at the right of Fig. 1. The 125 top, however, is self-supporting save as jars or the wind might tend to tilt it bodily about the single pivotal support 3 upon which the whole structure is sustained.

As in the foregoing description, the two 130

bows 7 and 17 may be regarded as first and second outrigger bows in the order named, the first of said bows being of two-part articulated construction, and the second 5 likewise of articulated construction but of more than two parts; in other words it is connected with the main bow through the medium of the three links 11, 12 and 13. The latter may also be regarded as constituting a flexible connection between the 10 rear portion of the first named outrigger bow, the main bow and the supplemental bow.

Other modes of applying the principle of 15 my invention may be employed instead of the one explained, change being made as regards the mechanism herein disclosed, provided the means stated by any of the following claims or the equivalent of such 20 stated means be employed.

I therefore particularly point out and distinctly claim as my invention:—

1. In a top for vehicles and the like, the combination of a main bow; a two-part 25 articulated outrigger bow having its rear portion pivotally attached to said main bow; a lever pivotally attached to the forward portion of said outrigger bow and intersecting the same in the open position of 30 the top; a second outrigger bow pivotally attached to the forward end of said lever, the rear end of the latter having a flexible linked connection with said main bow; and a supplemental bow pivotally attached to 35 the rear portion of said first-named outrigger bow and operatively connected with said lever through said linked connections.

2. In a top for vehicles and the like, the combination of a main bow; a two-part 40 articulated outrigger bow having its rear portion pivotally attached to said main bow; a lever pivotally attached to the forward portion of said outrigger bow and intersecting the same in the open position of the 45 top; a second outrigger bow pivotally attached to the forward end of said lever; links connecting the rear end of said lever with said main bow at a point above the point of attachment of said first-named outrigger bow thereto; and a supplemental bow pivotally attached to the rear portion 50 of said first-named outrigger bow and to one of said links.

3. In a top for vehicles and the like, the combination of a main bow; a two part articulated outrigger bow having its rear portion pivotally attached to said main bow; a lever pivotally attached to the forward portion of said outrigger bow and intersecting the same in the open position of the 55 top; a second outrigger bow pivotally attached to the forward end of said lever; two links connecting said lever with said main bow at a point above the point of attachment of said first-named outrigger bow 60

thereto, the forward of said links being shorter than the other; and a supplemental bow pivotally attached to the rear portion of said first-named outrigger bow and to said forward link at a point between the 65 ends thereof.

4. In a top for vehicles and the like, the combination of a main bow; a two-part articulated outrigger bow having its rear portion pivotally attached to said main bow; a lever pivotally attached to the forward portion of said outrigger bow and intersecting the same in the open position of the top; a second outrigger bow pivotally attached to the forward end of said lever; two other links connecting said first-named link with said main bow at a point above the point of attachment of said first-named outrigger bow thereto, the forward of said links being shorter than the other; a supplemental bow pivotally attached to the rear portion of said first-named outrigger bow and to said forward link at a point between the ends of the latter; and another link directly connecting said second outrigger bow with the outer portion of said first outrigger bow.

5. In a top for vehicles and the like, the combination of a main bow; a two-part articulated outrigger bow having its rear portion pivotally attached to said main bow; a lever pivotally attached to the forward portion of said outrigger bow and intersecting the same in the open position of the top; a second outrigger bow pivotally attached to the forward end of said lever; two links connecting said lever with said main bow at a point above the point of attachment of said first-named outrigger bow thereto, the forward of said links being shorter than the other and the joint between said first-named and forward links being a lock-joint; and a supplemental bow pivotally attached to the rear portion of said first-named outrigger bow and to said forward link at a point between the ends of the latter.

6. In a top for vehicles and the like, the combination of a main bow; a two-part articulated outrigger bow having its rear portion pivotally attached to said main bow; a supplemental bow pivotally attached to such rear portion of said outrigger bow; a member pivotally attached between its ends to said supplemental bow and serving as an equalizer; members flexibly connecting said equalizer member with said main bow and with the outer portion of said outrigger bow; and a second outrigger bow flexibly attached to such last-mentioned member.

7. In a top for vehicles and the like, the combination of a main bow; a two part articulated outrigger bow having its rear portion pivotally attached to said main bow;

a supplemental bow pivotally attached to such rear portion of said outrigger bow; a member pivotally attached between its ends to said supplemental bow and serving as an equalizer; members flexibly connecting said equalizer member with said main bow and with the outer portion of said outrigger bow; a second outrigger bow piv-

otally attached to such last-mentioned member; and a link directly connecting said second outrigger bow with the outer portion of said first outrigger bow. 10

Signed by me, this 10th day of January 1919.

FRED K. LEWIS.
